UNITED STATES PATENT OFFICE.

GEORGE SHROSBREE, OF PORTLAND, OREGON.

DESIGN FOR A LAMP STAND.

Application filed December 5, 1927. Serial No. 24,383. Term of patent 3½ years.

To all whom it may concern:

Be it known that I, GEORGE SHROSBREE, a citizen of the United States, residing at Portland, in the county of Multnomah and State of Oregon, have invented a new, original, and ornamental Design for a Lamp Stand, of which the following is a specification, reference being had to the accompanying drawing, forming a part thereof.

Fig. 1 is a side view of a lamp stand showing my new design; and

Fig. 2 is a front view of the same.

I claim:

The ornamental design for a lamp stand, as shown.

GEORGE SHROSBREE.
